UNITED STATES PATENT OFFICE.

JOHN H. BASINGER, OF OKLAHOMA CITY, OKLAHOMA.

TYPEWRITING MACHINE.

Application filed October 20, 1921. Serial No. 509,132.

This invention relates to typewriting machines in which electro-magnets are used to actuate the type-bars, either by their own force or to put them into operative connection with some other actuating member, and the object of the invention is to provide means by which two or more keys may be manipulated simultaneously to write in their proper order the letters of a word or 10 a syllable or any group of letters, and, by such improved means in combination with the usual means of operating typewriters of the character described, to provide a machine capable of higher operating speed.

15 This object is obtained by the mechanism illustrated in the accompanying drawings, in which:

Fig. 1 is a diagram of a part of the electric elements and connections of a typewriter having five sets of keys showing the parts that are involved in writing four letters, r t y u; Fig. 2 is a vertical section thru the actuating mechanism of an automatic typewriter in connection with mechanism for actuating an operating member; Fig. 3 is a vertical section thru a keyboard on the line i i in Fig. 4, Fig. 5, and Fig. 6 at the side of the keys B, G and T and thru the key above; Fig. 4 is a front view of a 20 part of the keyboard showing four columns of keys; Fig. 5 is a top view of the same; Fig. 6 shows the part of a switch board behind the keys shown in Fig. 4 and Fig. 5; Fig. 7 shows a switch, open at the left, closed at the middle and automatically opened at the right.

In all the several views similar letters and numerals refer to similar parts.

This improvement is adapted to be used 40 in any typewriter in which electro-magnets are used to actuate the type bars either by their own force or by putting them into operating connection with some other actuating member. In either case such magnets are referred to herein as actuating magnets and as actuating the type bars. Also, the keys which are involved in closing electric circuits to energize these magnets are spoken of herein as actuating the type bars. 45 It is preferred to show the invention in connection with an automatic typewriter in which the type bars are actuated by a constantly revolving cylinder 44. A coupler 50 55 43 is attached to the key lever or type-actuating lever 42 and is put into operative con-

tact with the cylinder 44 by a clamp member 45. The member 45 turns on a pivot and is actuated by an electro-magnet 3 and a spring 61 attached above center. The magnet 3 actuates the lever 46 to turn the 60 clamp member and the spring moves off center and draws the member down and presses the coupler 43 against the cylinder 44, and the motion of the cylinder draws the coupler down and actuates the type-bar. 65

It is not the object of this specification to discuss the operative relation between the actuating magnets and the type bars. The mechanism herein described is that which controls the electric current thru the actuating magnets. 70

In this improvement in typewriting machines there are five sets of keys for the actuation of the one set of type bars. One key of each set actuates the same type bar by closing an electric circuit thru the coil of the one magnet which actuates that type bar. Each set of keys actuates the type bars for all the letters of the alphabet. The keys 1 constitute one of the five sets and are referred to as principal keys. These keys are actuated one after another in any order and the corresponding types are actuated in the same order. This set of keys when standing alone is a common means for operating electric typewriters but it becomes a part of this invention by combination and cooperation with new elements. 85

The keys 01, 02, 03 and 04 constitute four of the said five sets of keys and are referred to as auxiliary keys. There may be more or less than four sets of these keys and still be within this invention. The machine is operated by the simultaneous actuation of one key of each of these four sets in cooperation with the mechanism described in the following paragraphs. 90 95

Referring to Fig. 1 at R, T, Y or U it is seen that the coil of the type actuating magnet 3 is in the course of five electric circuits. It may be said that it is in a circuit having variations but it is preferred to treat them as five circuits. When either of these circuits is closed the magnet is energized or magnetized and actuates the corresponding type. One of the five circuits of each magnet is referred to as the main or primary circuit. These circuits are closed by the principal keys 1 described above. A magnet actuating the word spacer has one 100 105 110

circuit which is treated as a primary circuit and the key closing the circuit as a principal key.

The remaining four circuits of each magnet are referred to as lateral circuits, first, second, third and fourth. Each of these circuits has two switches at which the circuit is closed by the auxiliary keys cooperating with an operating member 30. The keys 01, 02, 03 and 04 close one of the two switches in the first, second, third and fourth lateral circuits respectively and the operating member 30 actuates a contact brush 31 to close the other of the two switches in each of the four circuits. The brushes are moved to connect successively the lines 1^a, 2^a, 3^a and 4^a, one terminal of the switch in the first, second, third and fourth lateral circuits respectively, with a line 5^a the other terminal of each switch in a common course of these circuits on the face of a dial 29. The line 5^a is continuous with the line 2 to the magnet 3. A line 4 connects all the magnets 3 with a battery 38. A magnet 15 is in a common course of all the primary circuits and all the fourth lateral circuits and a magnet 18 is in a common course of all the first, second and third lateral circuits.

There are two dials 29 on which the switch terminals in the lateral circuits are exposed, one dial on each side of the member 30 which carries brushes on both sides and is pivoted at the center of the dials. The member 30 is actuated by a ratchet 33 which has a rod 36 connected with a lever 39. A universal bar 40 is supported on the lever 39 below and within the stroke of any lever 42. The magnet 18 is in position to actuate the rod 36 and when any key 01, 02 or 03 is actuated, the magnet is in circuit and draws the rod down and the ratchet engages the teeth 37 on the operating member 30 so that the stroke of any lever 42 actuates the member 30 to move the brushes from one circuit to the next. A spring 35 retracts the rod 36 and supports the universal bar 40 and a ratchet 52 supports the member 30 in its advanced position. The magnet 15 is positioned to actuate the ratchet 52 and when any key 1 or 04 is actuated this magnet is in circuit and releases the ratchet and a spring 51 retracts the member 30 to its normal position.

When the operating member 30 is in normal position the brushes 31 rest on the lines 1^a in all the first lateral circuits so that the actuation of any key 01 closes the circuit and actuates the corresponding type. The magnet 18 actuates the ratchet 33 to engage the teeth on the operating member 30 and the stroke of the lever 42 actuates the member to move all the brushes 31 to the lines 2^a in the second lateral circuits. In the same manner the actuation of any key 02 moves the brushes to the lines 3^a in the third

lateral circuit and the actuation of any key 03 moves them to the lines 4^a in the fourth lateral circuits. When any key 04 is actuated the magnet 15 is in circuit and releases the ratchet 5^a and the spring 51 retracts the member 30 and returns the brushes to the first lateral circuits.

When all the auxiliary keys 01, 02, 03 and 04 of the same letter group are actuated at the same time the key 01 instantly closes the circuit and actuates the corresponding type and when the brush 31 is moved to the second, third and fourth circuits of the group as described these circuits will be closed successively and the type will be actuated repeatedly. When one key of each of the different sets and of different letters are actuated at the same time the brushes will be moved as described and the several types will be actuated in the order of the key-sets to which the actuated keys belong.

The cooperation of the parts as described above is illustrated in the following example, using capital letters to distinguish similar parts used in writing different letters:

Actuate simultaneously the keys 01 R, 02 T, 03 Y and 04 U: The key 01 R closes the circuit instantly and the magnet 18 actuates the ratchet 33 to connect with the operating member 30, the magnet 3 R actuates the type R, and the lever 42 R depresses the universal bar 40 and actuates the operating member 30 to move all the brushes 31 to the second lateral circuits; the brush 31 T closes the circuit of the actuated key 02 T and the magnet 18 actuates the ratchet 33 to connect with the operating member 30, the magnet 3 T actuates the type T and the lever 42 T depresses the universal bar 40 and actuates the operating member 30 to move all the brushes 31 to the third lateral circuits; the brush 31 Y closes the circuit of the actuated key 03 Y and the magnet 18 actuates the ratchet 33 to connect with the operating member 30, the magnet 3 Y actuates the type Y and the lever 42 Y depresses the universal bar 40 and actuates the operating member 30 to move all the brushes 31 to the fourth lateral circuits; the brush 31 U closes the circuit of the actuated key 04 U and the magnet 3 U actuates the type U, the magnet 15 releases the ratchet 52 and the spring 51 retracts the operating member 30 and moves all the brushes 31 to the first lateral circuits. The four letters will be written in the order r t y u.

The auxiliary keys may be used repeatedly when one key of each set is used so that the key 04 is involved or when any key 01, 02 or 03 is followed by the word-space key to release the operating member 30. They may be used interchangeably with the prin-

cipal keys or they may cooperate with the principal keys in writing long words, using a part or all the auxiliary keys before or after the principal keys.

5 The five sets of keys with the switches and electric connections pertaining to the keyboard are supported on a frame having a base 9 and a switch board 7 with a horizontal extension 10. The switches in the primary 10 circuits are situated at the base 9 and the switches in the lateral circuits which are closed by the auxiliary keys are on the switch board 7. Each of the principal keys is mounted on a reach 11 pivoted near the 15 front of the switch board 7 and has a plunger 17 by which it closes the switch in one of the primary circuits at the base when the key is depressed.

The auxiliary keys 01, 02, 03 and 04 are 20 carried on the reaches 11 of the principal keys 1 by stems 5 passing thru standards erected on the reaches. The heads of the four auxiliary keys for one letter are closely assembled on one reach and constitute the 25 head of the principal key for another letter. The top of the two upper keys 03 and 04 are flattened and together they form the face of the principal key. The keys auxiliary to any principal key are carried 30 on the reach, and combined with the principal key next behind and above so that when the palm of the finger rests on the face of the principal key the keys auxiliary thereto are immediately at the finger tip. 35 The keys auxiliary to the principal keys of the first or front row are combined with the principal keys of the second row. The auxiliary to the principal keys of the third row combined with the keys of the fourth row. 40 The keys of the fourth row have no auxiliary keys. In typewriters having only about thirty type bars and three rows of keys the keys auxiliary to the principal keys of the third row are supported from the top 45 of the frame 10.

The principal keys are actuated downward one at a time by the palm touch of the finger. The auxiliary keys are actuated horizontally by the tips of the fingers, several of which (one of each set) are actuated simultaneously by a forward thrust of one or both hands. The switch shown in Fig. 7 is used in the primary circuits and the first 50 lateral circuits. A spring member 20 is tensioned to open circuit and closes the switch when driven against an inclined contact 19

by a plunger 17 actuated by the key. When the spring encounters the incline it moves aside the plunger and opens the circuit while the finger rests on the actuated key. 60

In the second, third and fourth lateral circuits two points of the switch are exposed on the face of the switch board 7. The switch 6^a is closed by flexible contact pads 6 carried on the stems 5 of the auxiliary 65 keys 02, 03 and 04 when the keys are actuated horizontally.

I claim:

1. In a typewriting machine, a set of electromagnets of which each magnet actuates 70 one type bar and is in a common course of five electric circuits, one set of principal keys of which each key is actuated to close one circuit of one of the said magnets and actuates the corresponding type bar, four 75 sets of auxiliary keys of which the keys of each set are actuated to close one of two switches in one circuit of each magnet, an operating member which, when in any position, closes simultaneously the other of two 80 switches in all the circuits wherein one switch is closed by the keys of one set and thereby cooperates with any actuated key of that set to close the circuit and actuate the type corresponding to the actuated key and 85 which operating member is actuated, by means disclosed, to close successively the other of the two switches in each of the four circuits of each magnet wherein one switch is closed by a key of a different set 90 and thereby cooperate successively with four keys, when one key of each of four sets are actuated simultaneously, and close four circuits and actuate successively four types corresponding to the four actuated keys. 95

2. In a typewriting machine, one principal key mounted on a reach which is supported on a pivot and which key is actuated downward and closes one circuit in one magnet and actuates one type bar and having 100 four auxiliary keys which actuate the same type bar and which are positioned immediately above and behind the face of the principal key and which are supported on the reach of a key other than the said principal key and are actuated horizontally to 105 close the switches and cooperate with the operating member to close the circuits and actuate the corresponding types in the manner and for the purpose disclosed.

JOHN H. BASINGER.
